UNITED STATES PATENT OFFICE.

WILLIAM F. MOON, OF MILWAUKEE, WISCONSIN.

SPECK-REMOVER.

1,309,258.

Specification of Letters Patent.

Patented July 8, 1919.

Application filed January 3, 1919. Serial No. 269,471.

To all whom it may concern:

Be it known that I, WILLIAM F. MOON, a citizen of the United States, and resident of Milwaukee, in the county of Milwaukee and 5 State of Wisconsin, have invented new and useful Improvements in Speck-Removers, of which the following is a description, reference being had to the accompanying drawings, which are a part of this specification. 10 The invention relates to a device for removing lumps of fiber or what are commonly called "specks" from yarn or thread, previous to its use in a spinning or weaving machine, and is fully described in the specification and shown in the accompanying 15 drawing in which:

Figure 1 is a bottom plan view of the machine embodying the invention; Fig. 2 is a section taken on the line 2--2 of Fig. 1; 20 Fig. 3 is a detail top plan view of the machine; Fig. 4 is a section taken on the line 4--4 of Fig. 3; Fig. 5 is a detail view similar to Fig. 2 showing a modified form of construction; Fig. 6 is a section taken on 25 the line 6--6 of Fig. 5.

In the drawings, the numeral 5 designates generally the frame of the machine, 6 a drive shaft mounted in said frame and provided with a pulley 7 driven from any suitable source of power, and 8 a driven shaft 30 mounted in the frame and carrying a bevel gear 9 meshing with a bevel gear 10 on the shaft 6.

In the drawings I have shown a plurality 35 of "speck" removing devices, each of which successively acts upon the thread to remove any specks therefrom so that if the first device does not remove the speck it will be removed by another of the devices.

40 Each of these speck remover devices is mounted upon side frame members 11 and consists generally in means for presenting the speck in position in which it may be readily severed from the thread or yarn by 45 the cutters or shears hereinafter described.

The means for presenting the speck in 50 position for removal consists of a pair of guide plates 12 and 13 which are slightly spaced apart to form a slit 14, and means 55 for turning the thread so that when it passes through the slit the speck on the thread will be presented below the slit. This means consists of a pair of sector shaped blocks 15 which are yieldingly held together and 55 against the plates 12 and 13 by means of

springs 16, each having one end disposed in a radial slot 17 in each block and the other end disposed in a radial slot 18 in one of the spaced frame members 19. The pressure of the blocks upon the plates may be 60 regulated by varying the pressure of the springs against the blocks by means of adjustable screws 20 bearing against the ends of the springs in the slots 18 of the member 19. The blocks meet each other at their 65 lower ends 21, but are separated at their upper ends 22 so that the thread or yarn may be readily threaded into the slit 14 by passing said thread down between the space between the member 19 and between the 70 yieldingly mounted blocks 15. The thread is turned by means of beveled portions 23 on the ends of the blocks which, when the thread advances, deflects the speck on the thread downwardly, thereby turning or 75 twisting the thread which brings the speck below the level of the plates 12 and 13. When the speck is thus brought down below the slit it is severed from the thread by means of a reciprocating cutter 24, or a 80 rotary cutter 24' which coacts with the plate 12 to shear or cut the speck off from the traveling thread as the cutter 24 or 24' is spaced slightly away from the plate 13, but 85 slides on plate 12.

The cutter 24 for each device is adjustably secured to a slide block 25 movable in a guide notch 26 in one of the members 11 and upon a frame strip 27. Each block 25 is reciprocated back and forth by means of an 90 eccentric link 28 which is pivotally connected at one end to the block and mounted at its other end upon an eccentric 29 on the shaft 8. The eccentrics for the different devices are set at different crank angles on 95 the shaft so that the cutters 24 of the different devices will operate at different times so that should a speck pass through the first device or devices when the cutter is on its return movement it will be severed by the 100 cutter of the next device which is on its forward movement.

The cutter 24' is a rotary knife mounted on a shaft 30 carrying a bevel gear 31 meshing with a bevel gear 32 mounted on a shaft 105 33 and a series of the devices provided with the cutters 24' may be provided in which instance all the shafts like the shaft 33 may be connected up to a common drive shaft.

The plates 13 are adjustably secured to 110

the frame by screws 13' and the cutters 24 are adjustably secured to the blocks 25 by screws 25'.

It will be understood that any changes in 5 the precise embodiment of the herein disclosed invention may be made as come within the scope of the claims.

What I claim as my invention is:

- 10 1. In a yarn speck remover, the combination of means for guiding the thread, means for turning the thread to bring the speck below the guide means, and means for cutting the speck from the thread as it advances through the guide means.
- 15 2. In a yarn speck remover, the combination of a pair of spaced apart plates and a support for the thread beneath the plates, means for turning the thread as it advances between the plates to present the speck below the plates, and means for severing the speck thus presented from the thread.
- 20 3. In a yarn speck remover, the combination, of a pair of plates spaced apart to form a guide slit, a support adjacent the plates having a beveled notch in line with the slit and adapted to be engaged by the speck on

the advancing thread for turning the thread to present the speck below the guide slit, and means for severing the speck thus presented from the thread.

30

4. In a yarn speck remover, the combination of a frame, means for guiding the thread, a pair of yieldingly mounted blocks in said frame adjacent said guiding means for bringing the speck below the guide means, and means for cutting the exposed speck from the advancing thread.

35

5. A plurality of devices as specified in claim 1 to successively act upon the advancing thread.

40

6. In a yarn speck remover, the combination, of a pair of plates spaced apart to form a guide slit, a pair of yieldingly mounted thread supports adjacent said plates and having registering beveled corners to form a notch in line with the slit and adapted to be engaged by the speck on the advancing thread to turn the speck for cutting, and means for cutting the speck from the thread.

45

In testimony whereof I affix my signature.
WILLIAM F. MOON.
